Primary Examiner—Alan P. Douglas

Assistant Examiner—Clare E. Heflin

(74) Attorney, Agent, or Firm—Joseph J. Previto

(57) **CLAIM**

The ornamental design for a foldable multi tool, as shown and described.

DESCRIPTION

FIG. 1 is a front view of my new design.

FIG. 2 is a top view thereof.

FIG. 3 is an edge view thereof.

FIG. 4 is another edge view thereof.

FIG. 5 is a view taken along line 5—5 of FIG. 1; and,

FIG. 6 is a bottom view thereof.

The broken line disclosure is for illustrative purposes only and forms no part of the claimed design.
